FURNACE WALL

Gerald F. Davey, Worcester, Mass.

Application May 25, 1934, Serial No. 727,549

14 Claims. (Cl. 72—101)

This invention relates to furnace walls, and more particularly to walls of the type having refractory blocks forming the fire face of the wall and supported independently of each other by a suitable framework.

It is one object of the invention to provide a wall which will be simple and inexpensive to manufacture and install, and which can be constructed entirely from blocks of a single shape.

10 It is a further object of the invention to provide a wall which can be constructed without the use of horizontal courses of unanchored key-bricks, and in which each block is firmly held in its proper place.

15 It is a further object of the invention to provide a wall having independently supported blocks which interfit in a novel manner to form a strong bond, and particularly to avoid horizontal joints in which molten slag may collect to cause spalling of the blocks.

20 It is a further object of the invention to provide a novel form of refractory block for use in walls of the supported type.

With these and other objects in view, as will be 25 apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a vertical section through a portion of a furnace wall, the section being taken on the line 1—1 of Fig. 6;

35 Fig. 2 is a side elevation of a refractory block; Fig. 3 is a top plan view of the block;

Fig. 4 is a front elevation of the block;

Fig. 5 is a rear elevation of the block;

Fig. 6 is a front elevation of the wall, with 40 certain of the blocks removed;

Fig. 7 is a view similar to Fig. 1 showing special blocks which can be used in certain cases;

Fig. 8 is a view similar to Fig. 1 showing a modified form of block and supporting structure;

45 Fig. 9 is a side elevation of the block shown in Fig. 8;

Fig. 10 is a top plan view of the block; and

Fig. 11 is a front elevation of the block.

In the drawings I have shown a supporting 50 structure or framework comprising a row of spaced vertical columns 15 to the front of which are secured a series of vertically spaced horizontal bars or beams 16. If desired, a vertical plate 17 may be fastened to the rear of the 55 columns 15, thus providing vertical passages

through which air may be circulated in a well known manner to cool the wall.

Each bar 16 as shown in Fig. 1 is substantially Z-shaped in cross-section and comprises an upwardly extending flange 19 which is fastened to the columns, a web 20 projecting forwardly toward the furnace and forming a horizontal shelf, and a flange 21 extending downwardly from the front edge of the web. The bars 16 serve to support horizontal rows or courses of blocks 23 formed of a suitable refractory material, such as fire-brick.

The lower rear portion of each block 23 rests against the flange 19 and web 20 of the bar therebeneath, and the flange 21 of the bar thereabove 15 engages a shoulder formed by the rear wall of a groove 25 extending across the top of the block. The block is thus locked firmly in place. The block is so shaped that it may be tipped laterally to clear the flange 21 and then be withdrawn forwardly toward the furnace. For this purpose the upper surface of the rear portion of the block, as well as the bottom of the groove 25, is curved or inclined downwardly toward one side of the block, as shown particularly in Figs. 4 and 5, in 25 order that the block may be tipped laterally without interference with the bar or block thereabove. If desired, the same result may be obtained by curving the lower surface of the block laterally, or both the upper and lower surfaces may be 30 curved.

The upper and lower surfaces 28 and 29 of the front portion of each block are preferably inclined laterally so that the blocks will interfit in a novel manner. In the construction illustrated, 35 the front portion of the block is shaped as a parallelogram in front elevation, with vertical side faces and laterally inclined upper and lower surfaces. This construction not only strengthens the walls, but it also avoids horizontal joints in 40 which molten slag might accumulate.

In very large walls it may be desirable to facilitate the removal of certain groups of the blocks 23 for replacement. For this purpose certain blocks may be formed with separate upper 45 and lower portions 31 and 32, as shown in Fig. 7, and a wedge brick 33 may be inserted between these portions from the rear. By first removing the wedge brick, it will be possible to lower the upper portion of the block sufficiently to clear 50 the flange 21 and allow withdrawal of the two portions of the block in a direction toward the furnace. The number and location of these special blocks will be dependent upon the extent and arrangement of the wall in each particular case. 55

The removal of a few special blocks will provide a space into which the standard blocks may be tipped laterally for removal, as indicated particularly in Fig. 6.

5 In Figs. 8 to 11 I have illustrated a modified construction comprising vertical columns 36 having a vertical plate 37 fastened to their rear surfaces, and horizontal bars 38 secured to their front surfaces. Each bar 38 comprises an upwardly extending flange 40 which is fastened to the columns, a forwardly projecting web 41, a flange 42 extending downwardly from the front edge of the web, and a rib 43 extending upwardly from the front edge of the web. Horizontal 10 rows of blocks 45 are supported by the bars. Each block is formed with a transverse groove 46 in its upper surface and a transverse groove 47 in its lower surface, these grooves being respectively engaged at assembly by the flange 42 on 15 one bar and the rib 43 on the bar beneath. In order to allow lateral tipping of the block without interference both the upper and lower surfaces of the rear portion of the block, as well as the bottoms of the grooves, are curved or inclined 20 laterally, as shown particularly in Fig. 11.

In some cases it may be desirable to provide overlapping joints in the side faces of adjacent blocks, and for this purpose I have shown the front and rear portions of the block 45 offset 25 from each other laterally, as indicated particularly in Fig. 10. This construction provides shoulders 48 which overlap the shoulders of the laterally adjacent blocks and thus reduce the leakage of air through the wall into the furnace. The upper and lower surfaces 51 and 52 of the front portion of the block are parallel and inclined laterally in the same manner as the corresponding surfaces of the blocks 23.

It will be noted that the refractory blocks are 30 supported by the bars independently of each other, so that the wall can be built as high as may be desired.

The downwardly extending flanges on the bars lock the blocks firmly in place. By tipping the 35 blocks laterally they can be inserted or removed without interference with the flanges. By providing the laterally inclined upper and lower surfaces for the blocks, I have obtained a strong interfitting construction, and at the same time 40 avoided horizontal joints in which slag may accumulate and cause spalling. The sloping joint between each block and the block above will allow the molten slag to drain freely under the influence of gravity. The wall is simple and inexpensive to manufacture and install, and no unanchored key-bricks are required.

Having thus described my invention, what I claim as new and desire to secure by Letters Patent is:

60 1. A furnace wall comprising a series of vertically spaced horizontal bars, a flange extending downwardly from each bar, and a row of refractory blocks mounted on each bar, each block having a shoulder which engages the rear surface 65 of the flange thereabove, and the upper surface of each block being spaced a sufficient distance from the bar and flange above to allow removal of the blocks by tipping them laterally to clear the flange.

70 2. A furnace wall comprising a series of vertically spaced horizontal bars, a flange extending downwardly from each bar, and a row of refractory blocks mounted on each bar, each block having 75 a transverse groove in its upper surface to

receive the flange thereabove, and the upper surface of each block being spaced a sufficient distance from the bar and flange above to allow removal of the blocks by tipping them laterally to clear the flange.

3. A furnace wall comprising a series of vertically spaced horizontal bars, a flange extending downwardly from each bar, and a row of refractory blocks mounted on each bar, each block having a lower surface contacting with the bar beneath and an upper surface interlocking with the flange thereabove, one of said surfaces being inclined laterally to allow removal of the block by tipping the same laterally to clear the flange.

10 4. A furnace wall comprising a series of vertically spaced horizontal bars, a flange extending downwardly from each bar, a rib extending upwardly from each bar, and a row of refractory blocks mounted on each bar, each block having a transverse groove in its lower surface to receive 15 the rib therebeneath and a transverse groove in its upper surface to receive the flange thereabove, one of said surfaces being inclined laterally to allow removal of the block by tipping the same laterally to clear the rib and flange.

20 5. A furnace wall comprising a series of spaced parallel bars, a flange on one side of each bar, a rib on the other side of each bar, and a row of refractory blocks mounted on each bar, each block having a transverse groove in one surface 25 to receive the rib on one bar and a transverse groove in the opposite surface to receive the flange on the adjacent bar, one of said surfaces being inclined laterally to allow removal of the block by tipping the same laterally to clear the 30 rib and flange.

25 6. A furnace wall comprising a series of spaced parallel bars, a flange on one side of each bar, a rib on the other side of each bar, and a row of refractory blocks mounted on each bar, each block having a rear portion provided with a transverse 40 groove in one surface to receive the rib on one bar and a transverse groove in the opposite surface to receive the flange on the adjacent bar, each block also having a front portion providing a surface adapted to be exposed to the furnace 45 heat and shaped as a parallelogram with two acute angles and two obtuse angles.

7. A furnace wall comprising a supporting structure, and horizontal rows of refractory 50 blocks mounted on said structure, each block being shaped as a parallelogram in elevation and having vertical side faces and top and bottom surfaces which incline laterally in the same direction.

8. A furnace wall comprising horizontal rows 55 of refractory blocks, each block having a front portion shaped as a parallelogram in elevation and provided with vertical side faces and parallel laterally inclined top and bottom surfaces, each block also having a rear portion, and a supporting structure engaging the rear portions of the blocks to hold them in position in the wall.

9. A furnace wall comprising a series of vertically spaced horizontal bars, a flange extending 60 downwardly from each bar, and a row of refractory blocks mounted on each bar, each block having a rear portion shaped to provide a shoulder which engages the rear surface of the flange thereabove, each block also having a front portion provided with vertical side faces and top 65 and bottom surfaces which slope laterally from one side face to the other.

10. A furnace wall comprising a series of vertically spaced horizontal bars, a flange extending 70 downwardly from each bar, and a row of re- 75

fractory blocks mounted on each bar, each block having a rear portion provided with a transverse groove in its upper surface to receive the flange thereabove, each block also having a front portion provided with vertical side faces and laterally inclined top and bottom surfaces.

11. A furnace wall comprising a series of vertically spaced horizontal bars, a flange extending downwardly from each bar, and a row of refractory blocks mounted on each bar, each block having a rear portion shaped to provide a shoulder which engages the rear surface of the flange thereabove, each block also having a front portion provided with vertical side faces and laterally inclined top and bottom surfaces, the upper surfaces of the rear portion of each block being spaced from the bar above a sufficient distance to allow removal of the block by tipping the same laterally to clear the flange.
- 10 12. A furnace wall comprising a series of vertically spaced horizontal bars, a flange extending downwardly from each bar, and a row of refractory blocks mounted on each bar, each block having a rear portion shaped to provide a shoulder which engages the rear surface of the flange thereabove, each block also having a front portion provided with vertical side faces and laterally inclined top and bottom surfaces, the front 15 portion of each block being offset laterally with respect to the rear portion thereof.
- 15 20 25

thereabove, each block also having a front portion provided with vertical side faces and laterally inclined top and bottom surfaces, the rear portion of each block having a laterally inclined surface to allow removal of the block by tipping 5 the same laterally to clear the flange.

13. A furnace wall comprising a series of vertically spaced horizontal bars, a flange extending downwardly from each bar, and a row of refractory blocks mounted on each bar, each block 10 having a rear portion shaped to provide a shoulder which engages the rear surface of the flange thereabove, each block also having a front portion provided with vertical side faces and laterally inclined top and bottom surfaces, the front 15 portion of each block being offset laterally with respect to the rear portion thereof.

14. A refractory block for a furnace wall comprising a rear portion having provision for anchoring the block in place, and a front portion offset laterally from the rear portion and having vertical side faces and laterally inclined top and bottom surfaces.

GERALD F. DAVEY. 25
